UNITED STATES PATENT OFFICE

2,407,999

VEHICLE DOOR LATCH

Holden W. Rightmyer, Toledo, Ohio, assignor to
The American Swiss Company, Toledo, Ohio,
a corporation of Ohio

Application April 30, 1942, Serial No. 441,108

3 Claims. (Cl. 292—335)

1

This invention relates to vehicle door latches but more particularly to latches for automobile doors and an object is to improve the action of latches of this character to enable the door to be closed more easily.

Another object is to produce a door latch of the sliding bolt type in which the latch bolt is retained in retracted position substantially until the door is in closed position, thereby obviating the action usually necessary in latches of this character in which in the slamming of the door, the latch bolt is moved in a retracting direction during its movement over the keeper.

A further object is to produce a latch of the above character with which is associated the dovetail structure, the releasing element for the sliding latch bolt being associated with one of the dovetail members and operatively engaging the other dovetail member for releasing the latch bolt.

A still further object is to produce a new and improved door handle mechanism in which the handle occupies a minimum amount of space, is free from dangerous outwardly projecting parts and operates in a simple manner to retract the latch bolt by movement of the handle outwardly away from the door.

For purposes of illustration but not of limitation, embodiments of the invention are shown in the accompanying drawings in which

Figure 1 is a side elevation of the door latch mechanism and showing also the inside operated remote control structure, it being noted that the cover plate for the outside operated dogging mechanism is removed, legs therefore being shown in section;

Figure 2 is a front edge elevation partly in section of the latch mechanism shown in Figure 1;

Figure 3 is a transverse sectional view of a portion of the latch mechanism showing the same in relation to the dovetail keeper, some parts being removed for the sake of clarity;

Figure 4 is a perspective view of the latch bolt catch lever;

Figure 5 is an elevational view of the female dovetail keeper structure;

Figure 6 is a fragmentary elevation somewhat diagrammatic of an alternate form of latch mechanism in which the dovetail structure is omitted;

Figure 7 is a front edge view of the latch shown in Figure 6;

Figure 8 is a perspective view of the catch lever employed in the latch shown in Figures 6 and 7;

2

Figure 9 is a sectional view showing the outside operated door handle and associated door structure;

Figure 10 is an enlarged sectional view of the door handle assembly;

Figure 11 is an elevation of the door handle assembly as viewed from the outside of the door; and

Figure 12 is an enlarged sectional view of the door handle assembly taken approximately through the central portion.

The illustrated embodiment of the invention comprises a vehicle door latch having a case plate 10, one edge portion of which is bent upwardly to provide a flange or selvage plate 11. Slidable over the case plate 10 is a bolt plate 12 to which is riveted a bolt nose 13, the latter sliding through an opening in the selvage plate 11 to and from latching position. A spiral spring 14 has one end anchored to the case plate 10 and its opposite end engages the rear face of the bolt nose 13 for normally urging the latter to latching position. At the rear end of the bolt plate 12 is a downturned flange 14' which is adapted to engage a rubber bumper 15 carried by the case plate thereby to cushion the latching movement of the bolt plate.

From the outside of the door, the latch bolt is retracted by a roll back 16 which in this instance is of a two-part or scissors cam construction, a spring 17 urging these parts relative to each other in order to snugly grip the operating spindle which fits into the square hole 18. The scissors cam construction is well-known to those skilled in this art and since it forms no part of the present invention, detail description and illustration is not considered necessary. The latch bolt is retracted from the inside of the door by a remote control unit designated generally at 19, the same having an actuating arm 20 to which is pivoted a link 21. The forward end of the link 21 is pivoted to a slide 22 which has an elongate slot 23 through which extends a rivet 24. At the forward end of the slide 22 is an extension 25 which when the slide is moved forwardly relative to the bolt plate 12, the same may be disposed in blocking relation to the outside operated roll back cam 16 thereby blocking the bolt retracting movement of the roll back.

Projecting from the upper edge of the slide 22 is a flange 26 which is adapted to abut against an ear 27 struck outwardly from the bolt plate 12. Thus when the slide 22 is moved forwardly to dog the roll back 16, the flange 26 abuts against the ear 27 so that upon retracting move-

ment of the bolt, ear 27 engaging the flange 26 pushes the slide 22 rearwardly thereby releasing the outside operated roll back 16. The cooperation of the ear 27 and flange 26 provides slam-unlocking.

Mounted on an extension 28 of the case plate 10 is a vertically movable slide 29 which may be actuated by a cam 30. The cam 30 may be associated with a key operated lock so that by insertion of the key, the cam 30 may be turned in one direction or the other. By upward sliding of the dogging slide 29, the outside operated roll back 16 is blocked against movement.

Pivoted to the inner side of the selvage plate 11 and disposed in a plane at substantially right angles to the plane of movement of the bolt plate 12 is a catch lever 31. The catch lever 31 is pivotally mounted upon a rivet 32 and has an extension 33 which is adapted to abut against the case plate 10 for limiting swinging movement in one direction. A leg 34 depends from the lever 31 and has an inwardly bent arm 35 disposed at approximately right angles to the body of the lever 31. A spiral spring 36 has one end anchored to the case plate 10 and the opposite end engages in a notch portion 37 of the catch lever 31 and urges the catch lever 31 in a counterclockwise direction (Figure 1), thereby urging the arm 35 toward the case plate 10 and in this manner it will be manifest that when the bolt plate 12 is retracted a sufficient distance to move the bolt nose 13 away from its keeper, the free end of the arm 35 snaps into place and serves as a stop to block latching movement of the bolt plate. In this manner the bolt plate 12 is retained in its retracted position with the bolt nose 13 out of latching relation to its keeper.

Also integral with the catch lever 31 is a releasing arm 38 which extends at substantially right angles to the body of the lever 31 in a direction opposite to that of the arm 35. The arm 38 projects through an aperture 39 in the selvage plate 11 and is disposed inside of the male dovetail member 40 which is rigid with and projects outwardly from the outer side of the selvage plate 11. The dovetail member 40 is open on the inside and has tapered side walls and as indicated on Figure 2, the releasing arm 38 is positioned adjacent one end of the dovetail member 40 so that when the door on which the above described latching mechanism is mounted, is moved to closed position, the releasing arm 38 of the catch lever 31 abuts against the shoulder 41 of the female dovetail member 42. Opposite sides of the member 42 are correspondingly tapered to receive the male dovetail pair 40, a spring actuated shoe 43 in the dovetail part 42 being spring urged to bind the parts together. As shown, the member 43 slides on a pin 44 and is under yielding pressure from a spring 45 which encircles the pin 44. Forming part of the dovetail 42 is a keeper 46 having bolt engaging ledges 47 and 48, the ledge 47 providing the usual safety stop.

From the above description, it will be apparent that the latch bolt 13 is released by the catch lever 31 substantially when the male dovetail member 40 bottoms upon the female member 42. At substantially that time the bolt nose 13 being released by the arm 35, snaps abruptly to latching position as indicated by the broken lines on Figure 5.

The form shown on Figures 6 to 8 is similar to that above described except that the dovetail parts are omitted. In this form the catch lever 31a has an integral releasing arm 38a which en-

gages in abutment on the door jam for rocking the arm to release the bolt nose 13a as above described. As above described, the catch lever 31a also has an arm 35a which is adapted to hold the bolt plate 12a in its retracted position. The catch lever 31a is slightly different in form from the catch lever 31 above described but in general the structure and operation are the same. It will be observed that the selvage plate has an arcuately shaped slot 39a to afford the release arm 38a the desired movement.

In Figure 9, 50 designates the outside metal panel of an automobile door which is formed with a recess 51. The outside door handle 52 is curved with the free end abutting against an embossed knob 53 adjacent the recess 51. In this manner the handle is brought close to the side wall of the door thereby removing any dangerous projections and the recess 51 enables the handle 52 to be conveniently grasped. The handle 52 is provided with an enlarged end portion 54 which is mounted on a pivot pin 55. As shown in Figure 12, the handle 54 fits within a casing 56 and a sleeved escutcheon 57 is adapted to be fastened to the door structure. The portion 58 of the handle which projects beyond the pivot pin 55 is somewhat reduced and engages with a cam arm 59 which fits in an extension 60 of the casing 56. The cam arm 59 has a hub 61 which is provided with a squared opening to receive the spindle 62. The spindle 62 may engage at its opposite end in the outside operated roll back, as for example, by engaging the in the squared opening 18 of the roll back 16 (Figure 1).

Formed in the extension 60 is a stop 63 against which a portion of the end 58 of the handle is adapted to abut, thereby to limit the rocking movement of the handle 52 in one direction. The handle 52 is normally retained in the position shown in Figure 9 by a spring 64 which encircles the pivot pin 55 and is disposed within an apertured portion 65 of the enlarged portion 54 of the handle, one end of the spring engaging the escutcheon member 57 and the opposite end bearing against a portion of the handle. It will be obvious that upon pulling outwardly on the handle 52, the spindle 62 is rotated thereby to actuate the roll back for retracting the latch bolt.

It is to be understood that numerous changes in details of construction, arrangement and operation may be effected without departing from the spirit of the invention especially as defined in the appended claims.

What I claim is:

1. In a device of the class described, an automobile door latch having a case plate, a selvage plate at one edge of said case plate, a spring tensioned latch bolt slidable over said case plate and projectable through said selvage plate when in latching position, a spring tensioned catch lever pivotally mounted on the inner side of said selvage plate and adapted to block movement of said latch bolt when in retracted position, and hold same from movement to latching position, a releasing arm on said catch lever projecting through said selvage plate, a male dovetail member on the outer side of said selvage plate into the inside of which said releasing arm extends, a female dovetail member with which said male dovetail member cooperates, an abutment on said female dovetail member engageable by said releasing arm for rocking said catch lever thereby to release said latch bolt, keeper means for said latch bolt associated with said female dovetail

member and engageable by said latch bolt when the same is released by said catch lever.

2. In a device of the class described, an automobile door latch having a case plate provided with a selvage plate at one edge thereof, a spring tensioned latch bolt slideable over said case plate and projectable through said selvage plate when in latching position, a catch lever pivoted to the inner side of said selvage plate and disposed at one side of said latch bolt, said catch lever being pivoted on an axis substantially parallel to the plane of movement of said latch bolt, an arm on said catch lever, a stop on said latch bolt engageable by said arm when said latch bolt is in retracted position thereby to hold said latch bolt retracted, a releasing arm on said catch lever projecting at right angles therefrom through said selvage plate, a male dovetail member on the outer side of said selvage plate in the region of said second arm, said male dovetail member being hollow and said second arm extending therethrough, a female dovetail member for receiving said male dovetail member, a stop on said female dovetail member for receiving said male dovetail member, a stop on said female dovetail member engageable by said second arm when said male dovetail member has entered said

female dovetail member a substantial distance thereby to rock said catch lever to release said latch bolt, and a keeper associated with said female dovetail member and engageable by said latch bolt upon release thereof.

3. In a device of the class described, an automobile door latch having a case plate, a selvage plate at one edge of said case plate, a spring tensioned latch bolt slideable over said case plate and projectable through said selvage plate when in latching position, a spring tensioned catch member movably mounted on the inner side of said selvage plate and adapted to block movement of said latch bolt when the latter is moved to its retracted position and retain same from movement to latching position, a releasing element on said catch member projecting through said selvage plate, and a male dovetail member on the outer side of said selvage plate into the 10 inside of which said releasing element extends, whereby upon slamming the door said releasing element is adapted to cooperate with the female dovetail part which receives the male dovetail part for actuating the catch member sufficiently 15 to release the latch bolt to allow the latter to move to keeper-engaging position.

HOLDEN W. RIGHTMYER.
